UNITED STATES PATENT OFFICE.

DONALD ROBERT NAPIER TAYLOR, OF SYDNEY, NEW SOUTH WALES, AUSTRALIA.

PRINTING APPARATUS.

1,307,325.

Specification of Letters Patent. Patented June 17, 1919.

Application filed September 28, 1918. Serial No. 256,080.

To all whom it may concern:

Be it known that I, DONALD ROBERT NAPIER TAYLOR, a subject of the King of Great Britain and Ireland, residing at 435/7 Kent street, Sydney, State of New South Wales, Commonwealth of Australia, have invented new and useful Improvements in Printing Apparatus, of which the following is a specification.

10 My invention relates to a printing apparatus for reproducing a multiplicity of prints arranged in symmetrical relation, from a single negative, and an object of my invention is to provide an apparatus of this 15 character having simple and efficient means for adjusting the sensitized plate with relation to the negative, and registering means for accurately positioning a plurality of printing plates such as used in color printing.

20 I will describe one form of apparatus embodying my invention and will then point out the novel features thereof in claims.

25 In the accompanying prints, Figure 1 is a view showing in bottom plan one form of apparatus embodying my invention.

Fig. 2 is a longitudinal sectional view taken on the line 2—2 of Fig. 1.

30 Fig. 3 is a transverse sectional view taken on the line 3—3 of Fig. 1.

Referring specifically to the drawings, J designates a rectangular table having a plain upper surface and provided at its center with an aperture K recessed into the surface; in the recess will be a thick sheet of plate glass k. Vertically below the aperture K is a trough K' containing mercury tubes K² that are adapted to glow with light, when an electric current is switched on. Between the trough K' and the aperture K, is a shutter K³ that will be manipulated by a rod and handle K⁴. Transversely upon the surface of the table is a clamping frame L which may be adjusted transversely by manipulating the handwheel L' and screw or rack L², and may be adjusted longitudinally by manipulating the handwheel M. The transverse screw L², which is carried by the adjustable frame L has a threaded engagement with the transversely adjustable frame member L⁶. The frame member L⁶ which is adjustable transversely of the table is provided at intervals with clips or clamps L⁷ for engaging a sensitized plate l. The longitudinal screws L³ are connected by worm gearing L⁴ with an operating shaft L⁵ carrying

the hand wheel M. The means employed to effect the adjustments may be varied according to the fancy of the designer and may consist of screws, worms and 60 worm wheels or pinions acting directly upon racks; in either case the handwheels L', M will be used to operate the working parts. A lever arm N, pivoted at the point n, carries a screw N, at the lower end of which is a 65 presser foot N². A frisket frame O is hinged to the surface of the table at the point o, o, alongside the aperture K. The frisket frame consists of a frame in which is a pane of glass or other suitable transparent 70 medium; its function is to register position marks on the plate G' and on a sensitive first printing plate, so that duplicate plates, (as may be required) shall occupy the same place over the aperture K that was occupied 75 by the first plate. This is indispensable in color printing. Except when the frisket frame is turned over to overlie the aperture K, it will lie in a recess in the surface of the table, as shown in Fig. 2. 80

The single or manifolded image photographed upon the sensitive plate G' having been "developed" and "fixed," in the usual way, will henceforth be referred to as the original image, in order that the sequence of 85 operations, hereinafter described, may be intelligently grasped.

The original image on the plate G' will be laid on the plate glass k in the aperture K, and, by means of micrometer screws k', adjusted so that the marks upon it shall coincide with the register marks on the frisket O; the surface of the plate G', on which is the photographed original image, must be flush with the surface J of the operating 95 table. The means adopted to adjust a plate in the recess, over the plate glass k, as, e. g. micrometer screws, so that marks upon the plate shall be made to coincide with the registered marks on the frisket, are well known 100 to, and understood by, every mechanician. A suitably prepared printing plate, block or stone l (the position of which is shown by dotted lines in Fig. 1) will then be secured to the clamping frame L and properly 105 adjusted above the original image on the plate G', that had been laid on the plate glass k in the aperture K; this will be effected by manipulating the handwheels L', M. When the printing plate l has been accurately adjusted and positioned, the presser foot N² on the lever arm N, will be swung 110

around so as to overlie the aperture K and will then be screwed down, thus securing contact between the prepared surface of the printing plate l and the original image upon 5 the plate G', in position in the recess. The electric current will then be switched on, causing the mercury tubes K², below, to glow with light; the shutter K³ will then be withdrawn, thus exposing the original image 10 on the plate G' and the sensitive surface of the printing plate l, immediately above it, to the action of the light rays, the apparatus being then left until the original image has been, photographically, printed upon 15 the sensitized surface of the printing plate l. After the necessary lapse of time, the shutter K³ will be closed, or the light switched off, the presser foot N² will be released and swung back from the aperture K, 20 leaving the printing plate l free to be moved in any direction. If the desired direction of movement of the plate l be transversely the table, this will be effected by manipulating the handwheel L', if it be longitudinal, it 25 will be effected by manipulating the handwheel M the object being to expose a fresh surface of the sensitized printing plate l above the original image on the plate G' in the aperture, so that another duplicate of 30 the original image may be, photographically, printed upon the newly exposed sensitized surface of the printing plate l, alongside the transfer that had already been made. In this way, if the original image on the plate 35 G' comprised a series of ten identical photographs, and this series of ten was printed ten times upon the sensitized surface of the printing plate l one single "pull" in a suitable printing or litho press would produce 40 one hundred identical images of the original photographed image that was inserted into the camera. If the original image on the plate G' consisted of one photograph only, and this photograph was multiplied ten 45 times upon the sensitized surface of the printing plate l, the issue from the printing press would be ten images for one "pull".

When the whole sensitized surface of the printing plate l has been consecutively 50 printed with transfers of the original image, or the desired number of transfers has been made, the printing plate l will be removed from the table, the images printed upon sensitized surface will be "developed" and 55 "fixed" and the plate l will be handed to the lithographer to be prepared for printing operations in a manner that is well understood. If duplicate plates are required, as e. g., in color printing the fresh plate will 60 be adjusted above the original image on the plate G' in the recess by means of the register marks on the frisket O and the hand-

wheels L', M, so that the transfers printed on the fresh plate l shall coincide in every particular with the transfers printed upon 65 the first plate l the operation of printing transfers upon fresh plates l being repeated as often as may be necessary.

I claim—

1. A printing apparatus comprising a table 70 having an opening formed therein, a trough in said opening adapted to receive a negative plate, a source of light below said opening, a registering device hinged to the table and adapted to swing over said opening, a movable frame adapted to carry a sensitized plate, means for moving said frame longitudinally and transversely of said opening, and a presser foot pivoted to said table and adapted to be moved over said opening. 80

2. A printing apparatus comprising a table having an opening therein to receive a negative plate, a source of light below the opening, a main frame, a clamping frame movable over the table, a worm shaft journaled in the main frame and disposed over the table, a pair of threaded sleeves on the shaft and connected to said clamping frame, a pair of worm shafts below the table, threaded sleeves surrounding portions 90 of the pair of worm shafts and connected to said main frame, and means for actuating said shafts.

3. A printing apparatus comprising a table having an opening formed therein, a 95 trough in said opening adapted to receive a negative plate, a source of light below said opening, a clamping frame adapted to support a sensitized plate, means below the table for moving said frame longitudinally 100 of the table, and means above the table for moving the frame transversely thereof.

4. A printing apparatus including a table having an opening formed therein adapted to receive a negative plate, means for adjustably supporting a sensitized plate above said opening, and a registering device comprising a frame hinged to the table at one side of said opening, and a transparent plate in the frame having position marks thereon, 110 said frame normally lying upon the table at one side of the opening and the hinge connection between the frame and the table being at the inner side of the frame when the latter is in said position upon the table and permitting the said frame to be swung over the opening. 115

In testimony whereof I have signed my name to this specification in the presence of two subscribing witnesses.

DONALD ROBERT NAPIER TAYLOR.
